GASIFIER

George L. Reichhelm, Short Beach, Conn., assignor to The Gasifier Company, Short Beach, Conn., a corporation of New Jersey

Application December 5, 1927. Serial No. 237,958

20 Claims. (Cl. 123—122)

The present invention relates to improvements in gasifiers.

More particularly the present invention relates to means and methods for gasifying relatively heavy fuels such as heavy oils.

An object of the present invention is to provide a gasifier which may be embodied in relatively small space, whereby it is adaptable for use on motor cars, boats and in other places where space is an important factor.

A further object is to provide a gasifier which will start readily without the use of extraneous heating means.

A further object is to provide a gasifier for relatively heavy fuels adaptable for use in the ordinary type of internal combustion engine, which will cooperate with such an engine to deliver gasified fuel thereto in response to the requirements of such an engine.

20 A further object is to provide a gasifier which will cooperate with an ordinary type of internal combustion engine to automatically preserve a desired relationship between the air flowing into said gasifier for combustion for the functions of the gasifier and the air required for combustion in the cylinders of the engine.

A further object is to provide a combination of gasifier and internal combustion engine whereby the heat of the exhaust gases from said engine may assist in the gasifying process.

25 A further object is to provide a combination of gasifier and internal combustion engine in which the flow of air into the engine will induce a flow of gas into the gasifier to offset some of the resistance entailed in the gasifying process.

A further object is to provide a combination of gasifier and internal combustion engine having safety features whereby the flow of oil to the gasifier is stopped in the event that the engine becomes inoperative.

A further object is to provide a gasifier which may be readily started to perform its gasifying functions.

30 A further object is to provide a gasifier of improved efficiency and smaller dimensions than has been the case with prior practice.

A further object is to provide a combination of gasifier and internal combustion engine which will operate in synchronism with the demands placed upon said engine whether said engine is operating upon the suction principle or upon the supercharger principle.

A further object is to provide a combination of gasifier and internal combustion engine of the gasoline type in which heavy fuel may be used.

A further object is to provide a combination of gasifier and internal combustion engine in which heavy fuel may be used and in which the necessity for fine adjustment is obviated.

Further objects will appear as the description 60 proceeds.

Referring to the drawings—

Figure 9 is a bottom plan view of the structure shown in Figure 8;

Figure 10 is a view looking in the direction of the arrows 10—10 of Figure 3, said figure being an end view of a flow regulating valve;

Figure 11 is a view in side elevation of the mechanism of the valve shown in Figure 10;

Figure 12 is a view showing part of the structure shown in Figure 1, but with a connection for a supercharger; and

Figure 13 is a view showing part of the structure shown in Figure 3, but showing the connections for a supercharger.

The numeral 20 indicates the exhaust manifold of an internal combustion engine. Secured to 95 the member 20 as for example by the capscrews 21—21, is the gasifier 22, having novel features which will be described. The housing which comprises the manifold 20 also provides a passageway to be referred to hereinafter, communicating with the outlet of said gasifier, which passageway conducts gas from said gasifier into contact with the walls of the passageway for exhaust gases, whereby said walls will effect a change in the direction of the gas delivered by said gasifier 105 and also transfer heat from the exhaust gases to the gas delivered by said gasifier. Said gasifier 22 has means for admitting a regulatable supply of oil and a regulatable supply of air. The flow of oil and air is preferably responsive to the force 110

which causes the flow of air into the cylinders of the engine, whether said flow of air into the cylinders of the engine be due to the suction of the engine or due to a means for setting up a super-
5 atmospheric pressure, as for example, a super-
charger. The gasifier 22 operates generally under the principles described and claimed in ap-
plicant's copending applications Serial No. 492,237
and Serial No. 752,049. The gasifier disclosed
10 in the present application, however, has certain
features not disclosed in the prior applications
referred to, which features contribute toward
greater efficiency and compactness.

The gasifier 22 comprises a receptacle, which
15 for purposes of description may be said to include a combustion chamber 23 and a gasifying cham-
ber 24. From an inspection of Figure 3, it will be
noted that communication between the combustion
chamber 23 and gasifying chamber 24 is pro-
20 vided through the neck 25, which neck is unsym-
metrical relative to the chambers 23 and 24. Com-
municating with the chamber 23 is the nozzle 26
for delivering a mixture of oil and air into said
chamber 23. Said nozzle has novel features of
25 construction, which will be referred to hereinafter,
and sprays a mixture of atomized fuel into
said chamber 23. A spark plug 27 is provided for
igniting the mixture of fuel and air within said
chamber 23.

30 It will be noted that the walls of the chamber
23 converge toward the neck 25. The wall 28 of
the chamber 24 may be substantially flat on its
inner surface, but the inner surface of the op-
35 posed wall 29 of said chamber 24 is of rounded or
globular form, whereby to provide a pocket which
will promote the setting up of a swirl within said
chamber 24. As noted above, the neck 25 is not
symmetrical with the chambers 23 and 24 but is
40 inclined relative to the axis of the nozzle 26, the
side 30 of the neck 25 adjacent to the wall 29
being closer to said nozzle than is the opposite
side of said neck 25. By reason of the construc-
45 tion illustrated, swirls of the material within the
chamber 24 will have a tendency to project par-
ticles of material upwardly through the neck 25
into the chamber 23 for the purpose of submit-
ting said particles to treatment within the com-
50 bustion chamber 23.

The means for admitting a regulatable sup-
ply of air and oil to the gasifier 22 and the means
55 for insuring a quick starting of the gasifying
functions will now be described. Disposed at the
extremity of the gasifier 22, spaced from the
manifold 20, is the housing 31, which provides
50 the oil inlet 32 and the valve seats 33—33, which
valve seats cooperate with needle valves 34 and
35. Said needle valves 34 and 35 communicate,
55 respectively, with the oil inlet tubes 36 and 37.
Disposed in cooperating relationship with the
needle valve 34 is the air inlet valve 38, and co-
operatively associated with the needle valve 35
60 is the air inlet valve 39. Figures 10 and 11 show
features of the needle valve 34 and the air inlet
valve 38. The air inlet valve 38 comprises two
65 disks 40 and 41, of which the disk 40 is adjust-
ably fixed relative to the housing 31. The disk
41 is non-rotatably but slidably secured to the
needle valve 34. Said disks 40 and 41 have co-
70 operating apertures 42, which may be of any pre-
ferred contour, which apertures are adapted to
be moved into and out of registry with one an-
other for controlling the flow of air therethrough.
The needle valve 34 is urged to its seat by means
75 of the spring 44. The present invention contem-
plates means whereby the needle valve 34 is

opened as the disk 41 is turned to increase the
effective area of the apertures 42—42 in the co-
operating disks 40 and 41. According to the
80 illustrated embodiment of the present invention,
the disk 41 is provided with the lever 45, which
may be controlled from the dashboard of an auto-
mobile or the like, as, for example, like the
choke of an automobile. Said disk 41 is pro-
85 vided with a plurality of cam-shaped wedging
members 46—46 adapted to cooperate with a pin
47 connected to the needle valve 34. As the lever
45 is turned for the purpose of moving the disk
41 relative to the disk 40, the members 46—46
90 will wedge the pin 47 outwardly to open the cor-
responding needle valve 34. It will be understood
that the disks 40 and 41 may be held in engage-
ment with one another by any preferred means
(not illustrated). The disk 40 is held in adjusted
95 position by means of capscrews 48, which engage
the edge portion of the disk 40 to hold same
tightly upon a corresponding seat in the housing
31. The needle valve 35 and the air inlet valve
39 may be the same in essential particulars as
100 the needle valve 34 and air inlet valve 38. Ac-
cordingly, no detailed description of the needle
valve 35 and the air inlet valve 39 are necessary.
The lever 45 connected with the disk 41 of the
air inlet valve 39 is connected to be operated by
105 means cooperating with the air inlet means of
the internal combustion engine in a manner
which will be referred to further hereinafter.

The oil inlet 36 communicates with a chamber
49, which is disposed within the passageway 50,
which has communication with the air inlet
valve 38. Said chamber 49 has apertures 51—51
110 in its side wall communicating with the passag-
eway 50. The lower extremity of the chamber 49
is provided with the wall 52, which wall is dis-
posed in angular relationship with the oil inlet
36. The lower extremity of the oil inlet 36 is
115 flared, as indicated by the numeral 57 (see Fig-
ures 8 and 9), said flared extremity being notched
to provide distributing points 58—58. The end
wall 56 of the chamber 49 is provided with an
aperture 59 disposed adjacent to the extremity of
120 the oil inlet 36, whereby oil delivered through
the oil inlet 36 may pass through the aperture
59. The passageway 50 has a portion 50A of
generally cylindrical contour, having its axis sub-
stantially coincident with the axis of the oil tube
125 36, and having another portion 50B of generally
cylindrical contour, having its axis inclined from
the axis of the tube 36 toward the axis of the
tube 37. A recess 50C communicates with the
portions 50A and 50B of the passageway 50, which
130 recess 50C contains a tube 60 which is bent in-
termediate of its length to have axes parallel with
the axes of the portions 50A and 50B of the pas-
sageway 50. The upper extremity of said tube
60 communicates with the air valve 38. The said
135 tube 60 has apertures 61—61 adjacent to the wall
56 of the chamber 49, but is imperforate for a
considerable portion of its length. The firing
points of the spark plug 27 are disposed sub-
stantially at a level indicated by the line 62.
140 Below the imperforate portion of the tube 60,
said tube is provided with a plurality of apertures
63—63. The lower extremity of the tube 60 is
preferably closed. Said apertures 61 and 63 need
145 to be located only on that side of tube 60 adjacent
to the passageway 50.

The nozzle 26 will now be described. Said
nozzle includes the cylindrical member 64 hav-
ing the bottom wall 65, which bottom wall is
diametrically slotted, as indicated by the nu-
150

meral 66 in Figure 7. Adjustably carried within the cylindrical member 64 are a pair of fingers 67 and 68 (Figure 4), which fingers are secured to a common member 69, the position of which 5 may be adjusted by means of the screw-threaded shaft 70. By turning said shaft 70, the member 69 may be raised or lowered, which will result in the raising or lowering of the fingers 67 and 68 relative to the bottom wall 65. Said fingers 67 10 and 68 have end portions 71 and 72, respectively bent toward each other, for directing a mixture of air and oil from the nozzle 26 toward the side walls of the combustion chamber 23. Said side walls are preferably provided with flame plates 15 73—73, which may be composed of metal which will stand very high temperatures without deterioration. Metal suitable for the purpose may be chosen from alloys of nickel and chromium, certain of such alloys being known in the trade 20 as Nichrome and Q-alloy. The flame plates should be of relatively thin gauge material, whereby they will quickly reach at least a red heat. Said flame plates may have fingers 74—74 projecting therefrom, which aid materially in combustion. Said flame plates 73—73 have very 25 valuable functions in the operation of the present invention due to their catalytic action upon the mixture of oil and air being gasified. The cylindrical member 64 is provided with the apertures 75 (see Figures 3 and 4), which permit the 30 passage of air from the air inlet valve 39 through the cylindrical member 64 to the combustion chamber 23. The lower extremities of the flame plates 73, 73 may be bent toward each other as indicated by the numerals 73A—73A to form a 35 restricted aperture in the outlet from chamber 24 to increase the tendency of superficial particles of the gas stream within chamber 24 to be deflected back into proximity with the nozzle 26.

The gasified fuel passes from the gasifier 22 into the passageway 76, which leads to the inlet manifold 77 of the internal combustion engine, which manifold, as illustrated, includes the 40 branches 77A and 77B. Also communicating with the inlet manifold 77 is the passageway 78 which is provided by the casing 79. Said casing 79 has communication to the atmosphere in the construction shown in Figures 1 and 3 through the 45 valve 80, which comprises a hollow piston provided with a closed end 80A and a plurality of apertures 81—81 in its side wall. Said piston 80 is disposed within a wall of the casing 79 and is adapted to admit air to said casing when said 50 piston is raised a sufficient distance to provide access from the interior of said piston to the interior of said casing 79 through the apertures 81. Said piston 80 is connected to the lever 45 connected to the rotatable disk 41 of the air inlet 55 valve 39. Weights 82—82 may be provided for adjusting the force tending to close the piston valve 80. The numeral 83 indicates a bell crank having a connection through the rod 84 to any 60 convenient operating means, such for example, as the accelerator or fuel feeding button of an automobile or the like. Said bell crank lever 83 is provided with an end portion 85 adapted to press downwardly upon a pin 86 secured to the 65 piston rod 87 secured to the piston 80.

It will be noted that the gas produced by the 70 gasifier 22, in passing from the gasifier, is directed against the wall 88, which comprises the top wall defining the passageway for exhaust gases passing through the exhaust manifold 20. Said gas also passes in contact with the side wall

88A of said passageway. In the operation of the gas engine having the exhaust manifold 20, said walls 88 and 88A will, of course, be at high temperature. By reason of the fact that the gas passing from the gasifier 22 passes in proximity to the walls of the exhaust manifold 20, said gas will be maintained at high temperature up to the instant it passes into the cylinders of the engine. Moreover, inasmuch as the gas from the gasifier 22 strikes the wall 88A in a direction perpendicular to said wall, the tendency to deflect gases back into proximity with the nozzle 26 is still further increased and stratification of said gas is minimized. Another advantage of this construction is that the danger of flames from the gasifier reaching the region of commingling of the gas with the air from passageway 78 is reduced. 80

By reference to Figures 6 it will be noted that a baffle 89 is provided for separating the gas from the passageway 76 from the air entering through the passageway 78, until said gas and air have entered a material distance into the intake manifold 77. Said baffle 89 serves a double purpose. First, it provides a safety feature with the advantage that if flames from the gasifying chamber 24 should shoot down through the passageway 76, such flames will not reach the region at which the gas from the gasifier 22 mingles with the air from the passageway 78; and second, by 85 reason of the fact that the air from the passageway 78 is directed to the intake manifold 77 in substantially parallel relationship with the stream of gas from the gasifier, the incoming air will have an aspirating effect upon the gas, improv- 90 100 105 110 115 120 125 130 135 140 145 150

Referring now to Figure 12, the numeral 90 indicates a pipe, which may lead to a blower such as used in a supercharger for an internal combustion engine. Referring to Figure 13, the numerals 91—91 indicate pipes leading to said blower. Said pipes 90 and 91 may be supplied with air at superatmospheric pressure from the same blowing means. The numeral 92 indicates a valve connected to lever 45 of the oil inlet valve 35, whereby said oil inlet valve will vary its opening in response to the flow of air to the passageway 78 and to the nozzle 26.

The mode of operation of the above described embodiment of the present invention is substantially as follows. Relatively heavy oil may be admitted through the oil inlet 32. Air either from the atmosphere or from the blower of a supercharger is admitted through the valves 38 and 39. Referring to the operation of the invention 130 in combination with an internal combustion engine, it may be stated that the crank shaft of the internal combustion engine will be turned in the usual manner for starting purposes. Referring particularly to an engine which operates upon the suction principle, the turning over of the crank shaft of the engine will induce a subatmospheric pressure in the intake manifold 77, which intake manifold communicates with the passageway 76 and with the passageway 78 in the casing 79. 140 In starting, the lever 45 will be turned by the operator in a direction to move the apertures 42—42 in the disk 41 into communication with the apertures 42 in the disk 40. This communication allows air to pass into the passageway 50. Turning 145 movement of the disk 41 of the valve 38 produces a camming action upon the corresponding pin 47 by reason of the engagement of the wedging member 46—46 with said pin 47. Rotative movement of the disk 41 to admit air to the pas- 150

sageway 50 therefore also results in axial opening movement of the needle valve 34, allowing oil to pass from the oil inlet 32 into the oil inlet pipe 36. Said oil collects upon the distributing 5 points 58—58 at the lower extremity of the inlet pipe 36, and presents a relatively large surface area for contact with the surrounding air. Primary air, entering through the chamber 49 atomizes the oil which has collected at the outlet 10 of pipe 36 and said atomized oil will be projected through the aperture 59. The atomized mixture of oil and air passing through the aperture 59 is ignited by the spark plug 27, which, as noted above is located at or about the level of the line 15 62 in Figure 3, additional or secondary air for combustion being provided by the air delivered through the apertures 51—51 in the chamber 49. In addition, air is supplied through the apertures 20 61—61 in the tube 60, though in practice it may be preferred to omit said holes 61—61.

The holes 63—63 in the tube 60 are located beyond the region at which the spark plug 27 ignites the atomized oil, whereby the jets of air from said apertures 63 will not interfere with ignition by said spark plug. Said apertures 25 63 direct air transversely to the flow of the atomized fuel from the aperture 59 and cause a decided agitation in the stream of atomized fuel, causing said stream to burn with a blue flame, indicating 30 complete combustion. By reason of the thorough agitation provided, the oil delivered through the inlet tube 36 is totally consumed, whereby the gasifier and adjoining parts are quickly heated. The reduction of pressure within the 35 intake manifold 77 due to the suction of the engine of which said manifold forms a part will result in the lifting of the hollow piston 80, whereby air from the atmosphere will pass through the apertures 81—81 in the wall of said piston, allowing air to enter the passageway 78. Lifting of the piston 80 will result in movement 40 of the lever 45 of the air inlet valve 39 to permit the entrance of air through said valve 39. Movement of said lever 45 will also have the result 45 of producing a camming action between the members 46—46 and the pin 47 of the needle valve 35, opening said needle valve 35 and permitting oil to pass from the inlet 32 to the oil inlet 37. Oil will pass through the oil inlet 37, which oil 50 will be atomized by the air which has entered through the valve 39. Fingers 67 and 68 will cause the deflection of the atomized oil, and said atomized oil will be ignited by the flame produced by the burning of the oil and air delivered 55 through the aperture 59. It will be understood, of course, that by regulating the rod 70, the position of the fingers 67 and 68 relative to the cylindrical member 64 may be adjusted, whereby said fingers may be set to correspond to the grade of 60 oil being used. Said fingers divert the atomized fuel into proximity with the flame plates 73—73 and also cause the stream to flow at a lower velocity, whereby the stream of atomized fuel travels at a rate below the rate of flame propagation. It will be clear that by diverting a part 65 of the stream in a properly constructed chamber, the rate of flow of the diverted portion can be brought down to and below the rate of flame propagation. Assuming that the diverted portion 70 of the stream of atomized fuel is properly mixed with air, said diverted portion will burn with a blue flame. The main core of the stream is heated by the burning superficial envelope of fuel, and the main stream of fuel is converted 75 to a gaseous state. The greater the quantity

of flame produced and mixed with the main stream, the more nearly will the main stream of the fuel be converted into a fixed gas. Since the main stream is projected through the flame and is heated by direct contact with the flame, a very efficient heating is obtained. As noted above, a portion of the atomized oil delivered by the oil inlet 37 is projected against the flame plates 73—73. Said flame plates 73—73 have serrated edges and projections extending into the projected portion of the main stream of atomized fuel, resulting in a thorough mixture of said projected portion of the projected fuel and retarding the flow of that part of the atomized fuel coming in contact with said flame plates. Each projection of the flame plates 73—73 reduces the velocity of flow and causes a change in direction which effectually reduces the rate of flow below the rate of flame propagation. Moreover, the flame plates 73—73, after they become heated to a red heat or above, have a catalytic action upon the atomized fuel, still further improving combustion. Air for providing complete combustion of the superficial particles of the fuel stream is provided through the apertures 75—75 in the cylindrical member 64, which air burns in the gaseous atmosphere. The gaseous fuel, the superficial particles of which are burning with a blue flame within the chamber 23, is projected through the neck 25 into the gasifying chamber 24. As noted above and as shown in Figure 4, the lower extremities of the flame plates 73 are bent inwardly from the walls of the chamber 24 forming a restriction. Moreover, the outlet of the chamber 24 is restricted relative to the globular wall 29 so that the force of the fuel from nozzle 26 tends to cause gas to be deflected back into proximity with said nozzle 26 for more complete combustion with the air emitted from the holes 75. This deflecting action is aided by the wall 38 of the exhaust manifold 22. The flat wall 28, the rounded or globular wall 29 and the angularly disposed neck 25 permit the efficient deflecting of the gas in the manner just referred to. Very thorough treatment of the gaseous fuel is therefore assured, the superficial particles of the fuel burning with a blue flame and traveling in a swirling path, which prevents the deposition of carbon upon the walls of the gasifier. The gasified fuel from the gasifier 22 and air from the piston valve 80 are intermingled in the inlet manifold 77 and are delivered to the cylinders of the engine in heated condition, rendering the starting of the engine comparatively easy. The passage of exhaust gases through the exhaust manifold 20 results in the heating of the walls 88 and 88A, which walls are in position to communicate heat to the gasified fuel passing from the gasifier 22, raising the temperature of said gas to a still higher point. Inasmuch as the upper surface 88 of the passageway for exhaust gases is so positioned that the gas impinges thereon, said surface helps in causing a more homogeneous mixture of the gas. Inasmuch as this mixture occurs in a very highly heated state, a gas is delivered to the inlet manifold which is quite homogeneous, avoiding difficulties which might occur through stratification.

As noted above, the piston valve 80 is weighted as for example, by means of the weights 82—82. Said weights 82—82 may be so chosen that a balance is preserved between the air required for combustion within the gasifier and the air required to mix with the gasified fuel delivered from said gasifier.

It will be noted that if the engine should fail, for any reason, whereby a subatmospheric pressure would not be induced within the passageway 78, the piston valve 80, being weighted, would fall, carrying with it the lever 45, resulting in turning movement of the corresponding disk 41 of the valve 39, which would move the wedging members 46 out of camming relationship with the pin 47, and allowing the needle valve 35 to close. 5 By reason of this construction, therefore, there will be no flow of oil into the gasifier when the engine is inoperative. From an inspection of Figure 1 it will be noted that the inlet manifold 77 is a branched manifold having the two passageways 77A and 77B, each of which passageways may feed a multiplicity of cylinders. The air passing from the passageway 78 passes through the manifold to the two passageways 77A and 77B, the passage of said air having an 10 injector action relative to the gas passing from the gasifier 22 through the passageway 76. Said injector action at least partially overcomes the friction to which fluid is subjected in passing through the gasifier 22, which friction is greater 15 than the friction of the air passing through the passageway 78.

As noted above, the bell crank lever 83 may be connected to a fuel feeding button of a self-propelled vehicle. The subatmospheric pressure 20 within the passageway 78 will tend to cause an opening movement of the piston valve 80, which opening movement will be resisted by the end portion 85 of the bell crank lever 83. The amount of this resistance will be controlled by the rod 33 25 which may be biased to a position in which valve 80 is held closed, but which may be moved from biased position by pressure on a gas feeding button or the like.

By reason of the present invention, a gasifier 40 is provided which is relatively compact, which may be readily started, and which cooperates in a most efficient manner with an internal combustion engine, whereby upon turning over the engine, as in the ordinary starting process, the 45 ignition having been turned on and the ordinary choke having been operated, the gasifier will be started and in a very short period of time will deliver a heated gas to the engine in combination with the necessary air to form a combustible mixture for engine running purposes. A predetermined ratio is maintained between the gas and air entering the inlet manifold and moreover the oil supply is automatically cut off if the engine 50 should fail, as for example, by stalling or by 55 failure of the ignition.

The operation of the modification shown in Figures 12 and 13 will be clear without detailed explanation, it being understood that the pipes 90 and 91 are connected to a blower or other 60 means for setting up a superatmospheric pressure.

Many modifications of the present invention 65 will occur to those skilled in the art. It is intended to cover all modifications that fall within the scope of the appended claims.

I claim:

1. In a gasifier, in combination, a receptacle, a 70 nozzle for projecting a mixture of oil and air into said receptacle, the inner wall of said receptacle having a rounded portion forming a pocket for setting up a swirl within said receptacle, the entrance to said pocket being provided by a neck disposed in angular relationship with the axis of said nozzle to deflect particles of said projected mixture back into proximity with said nozzle,

said nozzle being provided with apertures for supplying air into cooperative relationship with said deflected particles.

2. In a gasifier, in combination, a receptacle, a nozzle projecting into said receptacle, said nozzle comprising oil inlet means and air inlet means, said oil inlet means and air inlet means being disposed in cooperative relationship with one another whereby to project atomized oil into said receptacle, said receptacle being provided with a rounded portion in its wall to deflect portions of the stream projected by said nozzle back into proximity to said nozzle, the entrance to said rounded portion being provided by a neck disposed in angular relationship with the axis of said nozzle, said nozzle being provided with apertures for delivering air to the deflected portion of said stream.

3. In a gasifier, in combination, a chamber, a nozzle for projecting a mixture of oil and air into said chamber, said chamber being provided with means for deflecting a portion of said mixture back into proximity to said nozzle, an air inlet valve and an oil inlet valve for controlling said mixture of air and oil, means for normally urging said oil inlet valve to closed position, and means positively and mechanically connecting said oil inlet valve with said air inlet valve to cause said valves to move in synchronism with one another.

4. In a gasifier, in combination, a chamber, a nozzle for projecting a mixture of oil and air into said chamber, said chamber being adapted to deflect a portion of the stream projected from said nozzle back into proximity to said nozzle, said gasifier being provided with air delivery jets for supplying air to said deflected portion of said stream, igniting means, and means for delivering a mixture of fuel and air into proximity with said igniting means, said delivery means being adapted to project a flame into the stream delivered by said nozzle.

5. In a gasifier, in combination, a chamber, a nozzle for projecting a mixture of oil and air into said chamber, said chamber being adapted to deflect a portion of the stream projected from said nozzle back into proximity to said nozzle, said gasifier being provided with air delivery jets for supplying air to said deflected portion of said stream, igniting means, means for delivering a mixture of fuel and air into proximity with said igniting means, said delivery means being adapted to project a flame into the stream delivered by said nozzle, and means cooperating with said delivery means to deliver air transversely to the stream delivered by said delivery means, whereby to quickly heat up said gasifier.

6. In a gasifier, in combination, a chamber, a nozzle for projecting a mixture of oil and air into said chamber, said chamber being provided with means for deflecting a portion of the stream projected by said nozzle back into proximity to said nozzle, said gasifier being provided with means for projecting air into the deflected portion of said stream, igniting means for said stream, said igniting means comprising means for delivering a mixture of oil and air into proximity to said stream, a flame plate within said chamber for causing eddy currents within said chamber, and air delivery means for projecting the mixture of fuel and air delivered by said igniting means into proximity with said flame plate.

7. In a gasifier, in combination, a casing providing a gasifying chamber, a nozzle for project-

- ing a mixture of oil and air into said chamber, igniting means comprising means for delivering a mixture of oil and air into proximity with the stream projected by said nozzle, and air delivery means for agitating the fuel delivered by said igniting means and for projecting same against a wall of said gasifier. 80
8. In a gasifier, in combination, a casing providing a gasifying chamber, a nozzle for projecting a mixture of oil and air into said chamber, igniting means comprising means for delivering a mixture of oil and air into proximity with the stream projected by said nozzle, and air delivery means for agitating the fuel delivered by said igniting means and for projecting same against a wall of said gasifier, said wall being provided with a flame plate of relatively thin heat resisting metal. 85
9. In a gasifier, in combination, a receptacle, 20 a nozzle for conducting a mixture of oil and air into said receptacle, said receptacle being provided with means for deflecting a portion of said mixture back into proximity to said nozzle, said nozzle including oil delivery means and air delivery means, valves for said oil delivery means and air delivery means and mechanical power transmitting means between said valves for causing them to move synchronously, said valves being biased to closed position. 90
10. In a gasifier, in combination, a receptacle, 25 a nozzle for conducting a mixture of oil and air into said receptacle, said nozzle including oil delivery means and air delivery means, and valves for said oil delivery means and air delivery means connected together to move synchronously, said valves being biased to closed position, said receptacle being provided with means for deflecting a portion of the stream projected by said nozzle back into proximity with said nozzle, said gasifier being provided with means for delivering secondary air to said deflected portion of said stream. 100
11. In combination, a gasifier, an internal combustion engine, said gasifier being provided with 30 a nozzle for projecting a mixture of oil and air and having a receptacle provided with means for deflecting a portion of the stream projected by said nozzle back into proximity with said nozzle, said gasifier being provided with means for delivering secondary air to said deflected portion of said stream, said internal combustion engine having a conduit for hot exhaust gases, said conduit having a wall disposed in the path of the stream projected by said nozzle and adapted to cooperate with the deflecting means of said chamber, to deflect part of said stream back toward said nozzle. 110
12. In combination, a gasifier, an internal combustion engine, said gasifier including delivery 35 means for gas, said internal combustion engine including a conduit for hot exhaust gases, said conduit having a wall positioned in the path of the gas delivered by said gasifier, said internal combustion engine having an inlet passageway and baffle means for separating the gas from said gasifier from the air from said inlet means until said gas and air reach a region distant from that which may be reached by flame from said gasifier. 120
13. In combination, a gasifier and an internal combustion engine having an exhaust manifold, 40 said gasifier including means for projecting a swirling mixture of flaming oil and air and having a gas delivery passageway, said gas delivery passageway being in thermal communication 125
- with said exhaust manifold, said internal combustion engine having an inlet manifold provided with air inlet means and baffle means extending into said manifold for causing the gas from said gasifier and the air from said air inlet means to take substantially parallel courses in thermal communication with each other before intermingling, whereby the air from said air inlet means will operate with an injector action upon the gas from said gasifier and whereby the air in said air inlet means will be preheated. 130
14. In a gasifier, in combination, a gasifying chamber, means for projecting a stream of oil and air into said chamber, and igniting means, 45 said igniting means including oil delivery means and air delivery means cooperating with said oil delivery means, said air delivery means being provided with an aperture disposed in proximity to said oil delivery means, said aperture providing a passageway for oil from said oil delivery means, said air delivery means being provided with holes for delivering secondary air to the fuel projected through said aperture, said holes being disposed in rear of the point at which said fuel is projected through said aperture. 135
15. In a gasifier, in combination, a gasifying chamber, means for projecting a stream of oil and air into said chamber, igniting means, said igniting means including oil delivery means, air delivery means cooperating with said oil delivery means, said air delivery means being provided with an aperture disposed in proximity to said oil delivery means, said aperture providing a passageway for oil from said oil delivery means, said air delivery means being provided with holes for delivering secondary air to the fuel projected through said aperture, and air delivery means for projecting air transversely of the stream delivered through said aperture, said holes being disposed in rear of the point at which said fuel is projected through said aperture. 140
16. In a gasifier, in combination, a gasifying chamber, means for projecting a stream of oil and air into said chamber, and igniting means, 50 said igniting means including oil delivery means, air delivery means cooperating with said oil delivery means, said air delivery means being provided with an aperture disposed in proximity to said oil delivery means, said aperture providing a passageway for oil from said oil delivery means, said air delivery means being provided with holes for delivering secondary air to the fuel projected through said aperture, said holes being disposed in rear of the point at which said fuel is projected through said aperture, and air delivery means for projecting air transversely of the stream delivered through said aperture, said last mentioned air delivery means being free from air delivery holes at a region spaced relatively close to said aperture but being provided with air delivery holes at a region spaced from said aperture. 145
17. In a gasifier, in combination, a chamber, a nozzle for projecting a mixture of oil and air into said chamber, said gasifier being provided with air delivery jets for supplying air to a portion of said stream, igniting means, and means for delivering a mixture of fuel and air into proximity with said igniting means, said delivery means being adapted to project a flame into the stream delivered by said nozzle. 150
18. Mixing means comprising oil delivery means and air delivery means, said air delivery means comprising a chamber housing said oil delivery means and having an aperture, said oil delivery means being disposed in proximity to

- 25 said aperture in position to deliver oil through said aperture, said oil delivery means being provided with a plurality of oil collecting points adapted to be engaged by the air delivered by said air delivery means, whereby a finely divided mixture of air and oil is delivered through said aperture, said chamber being provided with holes for delivering secondary air to the stream of atomized oil delivered through said aperture.
- 10 19. Mixing means comprising oil delivery means and air delivery means, a chamber housing said oil delivery means and having an aperture, said oil delivery means being disposed in proximity to said aperture in position to deliver oil through said aperture, said oil delivery means being provided with a plurality of oil collecting points adapted to be engaged by the air delivered by said air delivery means, whereby a finely divided mixture of air and oil is delivered through said aperture, said chamber being provided with holes for delivering secondary air to the stream of atomized oil delivered through said aperture, said mixing means including air delivery means free of air delivery holes in a region spaced rela-
- 25 tively close to said aperture but provided with air delivery holes at a region at a greater distance from said aperture, said air delivery holes being positioned to deliver air transversely of the stream delivered from said aperture. 80
- 15 20. Mixing means comprising oil delivery means and air delivery means, a chamber housing said oil delivery means and having an aperture, said oil delivery means being disposed in proximity to said aperture in position to deliver oil through said aperture, said oil delivery means including air delivery means free of air delivery holes in a region spaced relatively close to said aperture but provided with air delivery holes at a region at a greater distance from said aperture, said air delivery holes being positioned to deliver air transversely of the stream delivered from said aperture. 85
